UNITED STATES PATENT OFFICE.

AMOS G. FITZ, OF AUBURN, MAINE.

LAST.

No. 817,966.

Specification of Letters Patent.

Patented April 17, 1906.

Application filed June 25, 1904. Serial No. 214,085.

To all whom it may concern:

Be it known that I, AMOS G. FITZ, a citizen of the United States, residing at Auburn, in the county of Androscoggin and State of Maine, have invented new and useful Improvements in Lasts, of which the following is a specification.

My invention relates to improvements in lasts which are divided transversely into a toe-section and a heel-section, which sections are linked or hinged together, and thereby capable of movement one relative to the other for shortening the last to enable it to be more readily inserted in and withdrawn from a shoe.

Some forms of my invention are illustrated in the accompanying drawings, in which—

Figures 1, 2, 3, and 7 are elevations, partly in section, showing different embodiments of my invention. Fig. 4 is an elevation showing a method of holding the last in broken position independent of the means for holding it in normal position. Fig. 5 is a horizontal sectional view of Fig. 4 taken on line X X; and Fig. 6 is a detail view in elevation of the link and contact shown in Fig. 1.

Same letters of reference refer to like parts in all the figures.

The object of my invention is to provide a last with means for maintaining the parts strongly but yieldingly in normal position, the construction of the parts and means for retaining them being such that when the parts are moved from normal to broken position the force tending to return and maintain the parts in normal position decreases gradually until the full broken position is reached, at which time such force becomes a practically negligible quantity, it being barely sufficient to start the parts on the return to the normal position, gradually increasing until the latter position is reached.

It has the further object to provide an independent means for holding a last in broken position.

I am aware that it is not new, broadly, to provide means for yieldingly locking the parts of a last in normal position; but so far as I am aware in all cases where this has been done the force impelling the parts to return to the normal position increases as the parts move from normal position, which is very objectionable, making it very difficult to place the shoe upon the last or remove it therefrom.

To carry out my invention, I provide the parts A and B of the last with suitable con-

necting means—for example, links C and D, pivotally connected one end in the heel part and the other end in the fore part. I then in one part, as the fore part, make a recess, in which the end of the link rests and in which is a socket E for the reception of the end of a coil-spring F. The outer end of the spring is adapted to engage the end of one of the links to some distance outside the pivot-point either directly or with a contact G, interposed between the spring and the end of the link. The outer end of the spring or the contact is free to bend downwardly and upwardly in its socket, the socket being large enough to permit such movement, so that when the link is turned on its pivot—upwardly, for example, as seen in Figs. 1, 2, 3, and 7—the direction of the pressure of the spring is brought nearer into line with the pivot upon which the link turns, thereby in proportion as it approaches said pivot lessening the force of the spring, tending to restore the parts to normal position. The relation of these parts should be such that when in position shown in dotted lines in said Figs. 1, 2, 3, and 7 the tension of the spring tending to return the last parts to normal position is very slight, being just sufficient to start them in that direction, but gradually increasing as the parts return to normal position, in which position they are strongly held. In Fig. 1 the intermediate contact has a round end H, adapted to rest in a round depression I in the end of the link. For convenience the link, as seen in Figs. 5 and 6, is provided with two plates or keepers J', one at either side, extending over said depression, thereby holding the contact from lateral movement relative to the link, the end of the contact having only a sliding movement in said depression. Fig. 2 differs from Fig. 1 only in the form of the contact, which here is pointed, the pivot-point changing from the upper to the lower side of the depression as the parts move from normal to broken position. In Figs. 3 and 7 there is no intermediate contact, the spring bearing directly against the link in Fig. 3, the end resting in a depression and in Fig. 7 the end receiving a projection on the link, in all cases the outer end of the spring being free to bend as the parts move from normal to broken position. In constructing the last the socket in which the springs rest may be of the same width as the kerf K, which receives the end of the connecting-link. In Fig. 7 I have illustrated a preferred means for preparing

the last for the reception of my invention. The kerf is made with any convenient tool—as, for instance, a saw. The socket E, of greater diameter than the width of the kerf, is bored in a longitudinal direction for the reception of the spring. A transverse hole M is then bored, intersecting the socket E beyond the bottom thereof, which permits the spring to be bent downwardly into the hole thus formed. It will be evident that the outer end of this latter hole may be plugged, if desired, so that the last will present an unbroken surface.

It will sometimes be convenient to have the last held permanently but lightly in broken position. For this purpose I provide the last with the overlapping structure shown and claimed in my application filed March 20, 1903, Serial No. 148,702, and at the side of the projection I place a disk spring N, which when the parts are moved from normal to broken position frictionally engages the inner wall of the opposite part, the friction being sufficient to barely retain the parts in broken position.

In operation the last is placed upon the spindle, the shoe partly drawn thereon while the last is in normal position. Pressure is then applied to the toe to move the toe part into broken relation, in which position the force tending to return is slight, and the shoe can be readily drawn thereon. The spring when the pressure is removed from the toe returns the parts to normal position and holds them strongly during the processing of

the shoe. When the shoe is to be removed, the operation is reversed.

Having thus described my invention and its use, I claim—

1. A last divided transversely, a union connecting the parts, whereby one part may have movement relative to the other, means interposed between the parts for yieldingly opposing movement of the parts, a portion of said opposing means being free to move vertically, the union and opposing means being constructed to offer yielding and decreasing resistance as the parts move away from normal position. 40

2. A last divided transversely, a union connecting the parts whereby one part is free to move, relative to the other, one part being provided with a spring-receiving socket, and a spring mounted in said socket and engaging said union, the size of the outer end of the 55 socket being greater than the size of the spring, and the outer end of the spring being free to move vertically, the spring and union being constructed and positioned to offer yielding and decreasing resistance as the parts 60 move away from normal position. 50

In testimony whereof I have signed my name to this specification, in presence of two subscribing witnesses, this 2d day of June, 1904.

AMOS G. FITZ.

In presence of—

JOHN A. MORRILL,
DAISY E. YOUNG.
